CAP AND PACKAGE

Charles Hammer, New York, N. Y., assignor to
 Anchor Cap & Closure Corporation, Long
 Island City, N. Y., a corporation of New York

Application June 28, 1930, Serial No. 464,435

18 Claims. (Cl. 215—40)

The present invention relates to the sealing art and more particularly to an improved cap and package.

Side seal closures are very popular in the sealing art due to the tight seal which they are adapted to make on containers varying considerably from a standard size. Usually, a bead in the skirt of the cap is provided with a gasket which is pressed firmly against the side wall of the container to hold the cap in place and to form a hermetic seal on the container. The bead of the cap may be reformed by suitable machinery in order to press the gasket against the container and to secure a very tight seal. Packages sealed in this manner are usually sterilized after being sealed; in other words, the products are packed in the packages and are thereafter heated in a suitable retort to about 240 degrees Fahrenheit, or some similar temperature, depending upon the products being sterilized. Such temperatures cause the formation of a pressure in the container which exceeds the steam pressure in the retort, thereby creating an unbalanced pressure tending to blow the caps from the containers. In addition, the temperature softens the vulcanized gasket in the skirt of the cap to such a point that the holding power of the cap is greatly impaired. The result is that many of the caps pop off and the contents of these packages are spoiled. Attempts have been made to remedy this by utilizing air pressure in addition to the steam pressure in the retort, whereby the pressures within the containers and the retort are balanced. In some instances, the seals were formed tighter upon the containers, but this caused a greater number of containers to be broken during the sealing operation. Various types of special containers have been provided but these were more expensive and not entirely satisfactory.

The present invention aims to overcome the difficulties enumerated above and to provide a very inexpensive sealed package which is fully capable of withstanding the high temperatures necessary to processing, without impairing the seal. The invention also contemplates the achievement of this result without increasing the cost of either the cap, the container or the sealing equipment necessary.

50 An object of the invention is to provide a sealed package which is fully capable of withstanding the high temperatures necessary in processing, without impairment of the seal.

Another object of the invention is to provide 55 an inexpensive package having a very secure

seal which holds the cap upon the container independently of the gasket.

Another object of the invention is to provide a closure cap adapted to form a secure seal on a package which may be readily removed from a container.

Another object of the invention is to increase the security of the seals made by side seal closures.

Other and further objects of the invention will be obvious upon an understanding of the 10 illustrative embodiment about to be described, or will be indicated in the appended claims, and various advantages not referred to herein will occur to one skilled in the art upon employment of the invention in practice.

15 A preferred embodiment of the invention has been chosen for purposes of illustration and description and is shown in the accompanying drawing, forming a part of the specification, 20 wherein

Fig. 1 is a side elevational view of the closure with a gasket therein, portions thereof being shown in section;

Fig. 2 is a fragmentary view illustrating the closure cap sealed to a package, with parts shown 25 in section; and

Fig. 3 is a fragmentary side elevational view with parts in section illustrating a package having another form of closure thereon.

Referring again to the drawing, there is shown 30 a container 1 which may be in the form of a tumbler with a cylindrical side wall sealing surface 2 and an annular bead 4 immediately above the sealing surface of the container. The side wall 5 of the container, intermediate the bead 4 35 and rim 6, is tapered substantially inward to facilitate the removal of the closure, as described hereinafter.

The closure cap shown more particularly in 40 Figs. 1 and 2, may comprise a cover portion 7 and a depending skirt 8 with a bead 9 therein and a depending skirt 8 with a bead 9 therein adapted to receive and seat a gasket 10. Preferably, the bead 9 is at the lower part of the skirt of the cap and has its lower side formed by the edge or turned bottom of the skirt.

45 Immediately above the bead of the cap there is provided a series of indentations 11 which may be of any suitable form, here shown as elongated and narrow. The length of the portions 12 of the skirt of the cap intermediate the indentations 11 may be increased or decreased, depending upon the amount of resilience desired in the portion of the cap directly above the bead. The longer the portions 12 and the shorter the indentations 11, the less holding power this part of 50 55

the cap will have. The converse is likewise true. The position of the portions 11 with respect to the bead 4 on the container is preferably such that the upper inner sides of the portions 11 lock 5 with the lower surface of the bead 4. With this type of cap, the gasket, when resting in the bead, as shown in Fig. 1, is adapted to clear the outer side wall of the container, including the bead 4, so that the cap rests loosely on the container 10 prior to the sealing operation. Preferably, the indentations 11 engage the bead 4 slightly prior to the sealing operation.

It will be understood, of course, that the sealing operation may be relied upon to effect the locking engagement of the indentations 11 with the bead 4. It is preferred, however, to use, a combination of these two effects, that is, to have the indentations engage the bead slightly prior to the sealing operation and have this engagement increase during the sealing operation. In this way, when the package is sealed, the indentations 11 will be forced firmly under the bead 4 to hold the cap in position. When the package is placed in a retort for processing or sterilization, the indentations 11, co-operating with the bead 4 on the container, are fully capable of holding the cap on the package irrespective of how soft the gasket 10 becomes or how little holding power it may have at the high temperatures. 25 Furthermore, the form lock between the metal and the glass makes it unnecessary to maintain an equalized pressure condition within and without the sealed containers. This will, of course, minimize the cost of the sterilizing equipment, 30 reduce the cost of operation, and increase the speed of the sterilizing operation. At the present time, great care must be utilized in bringing the containers up to temperature and in reducing their temperature to prevent the caps from popping off the containers. 40

The closure caps may be very easily removed by the application of a cap opener with the jaw engaging the bottom of the skirt and the fulcrum the cover part of the cap. In this manner, the indentations 11 may be pulled over the bead 4 and, after clearing the bead, the tapered portion 5 of the container permits the cap to be readily removed without further stretching thereof.

In Fig. 2, the indentations 11 are shown spaced 50 slightly above the upper side of the bead of the cap. It will be understood, of course, that the position of the indentations may be varied considerably without interfering materially with the operation thereof. It is desirable, however, to have the bead 4 of the container positioned with respect to the indentations 11 so that the indentations lock beneath the bead 4.

In Fig. 3, a slightly different embodiment is shown, wherein the upper side of the bead is 60 pressed inwardly so that the lower side thereof is flared outwardly. This increases the size of the skirt of the cap at the bottom thereof and facilitates the application of the cap opener to the cap. There is ample space between the bottom of the skirt and the side wall of the container for engagement of the jaw of the opener therewith. The indentations 11 therein are 65 shown directly adjacent the upper side of the bead. As illustrated, the lower sides of the indentations 11 are common to the upper side of the bead. The advantage in this type of construction is that the gasket 10 is sealed 70 directly below the bead 4 of the container, and thereby co-operates with the bead on the container to increase its holding power. As illus-

trated in Fig. 3, the gasket and indentations 11 both co-operate simultaneously with the bead 4 on the container to hold the cap in position. Where the indentations 11 are considerably above the bead 4, the gasket may not contact with the bead 4 on the container, and its holding power, apart from the rest of the cap, is slightly less than it is in the structure shown in Fig. 3.

In the sealing operation, the closure cap is mounted loosely over the mouth of the container, the projections 11 engaging slightly with the bead 4 on the container. Thereafter, the sealing chuck is applied, which presses downwardly on the cover part of the cap to press it firmly on the container and to hold it in this position while 15 suitable jaws or spinning tools are utilized to reform the bead in the closure cap, thereby extruding the gasket from the bead against the side wall of the container. The reformation of the bead of the cap reduces the size of the skirt 20 of the cap and brings the projections 11 more firmly into locking engagement with the bead 4 on the container, whereby the cap is held in position by both the mechanical seal between the metal and the bead on the glass container and 25 the hermetic seal between the gasket and the container. In the removal operation, a cap opener is applied to the cap to raise one side of the cap about the other and to stretch the skirt of the cap over the bead 4, after which the tapered 30 bevelled surface 5 permits free movement of the cap upward. This reduces the amount of stretching necessary to clear the upper edge of the container.

It will be seen that the present invention provides an inexpensive closure cap and sealed package which are fully capable of withstanding the high temperatures and pressures desirable in processing operations. The packages are adapted to minimize or eliminate the additional air 40 pressure within the retort in the sterilizing operation and are also adapted to minimize the number of packages lost or spoiled during the processing or sterilizing operation. The several 45 objects are achieved without increasing the cost of the cap or the package and without complicating the sealing operation. The increased security of the seal renders the package better adapted for the rough usage to which it may be subjected.

As various changes may be made in the form, construction and arrangement of the parts herein without departing from the spirit and scope of the invention and without sacrificing its advantages, it is to be understood that all matter herein is to be interpreted as illustrative and not in a limiting sense.

Having thus described my invention, I claim:

1. A sealed package comprising a container having an annular outward extension beneath the rim thereof, a closure cap having a cover portion and a depending skirt, the lower edge of the skirt of said cap being turned inwardly to support a gasket, a gasket in said skirt, and a plurality of spaced elongated projections in the 60 skirt of the cap in engagement with the extension on the container.

2. A sealed package comprising a container having an annular bead adjacent the upper end thereof, a closure cap having a cover portion and a depending skirt, said skirt having means to receive a gasket, a gasket in said skirt engaged with the container below said bead, and means in the skirt of the cap engaging the bead to co-operate with the gasket to hold the cap on the 70 75

container, said cap being removable from the container by raising one side of the cap over the side of the container.

3. A sealed package comprising a container having a substantially cylindrical sealing surface, an annular bead above said sealing surface, a closure cap having a cover portion and a depending skirt, a gasket in the lower part of said skirt, and means on said cap above said gasket engaging the bead on the container to co-operate with the gasket to hold the cap in position, said cap being removable from the container without removal of the gasket from the bead.

4. A sealed package comprising a container having a substantially cylindrical side wall sealing surface, a bead above said sealing surface, the outer side wall of the container being tapered inwardly adjacent the rim of the container to facilitate removal of the closure cap, a closure cap having a cover portion and a depending skirt, means formed in the skirt interlocked with said bead, and a gasket in the skirt of the cap engaging the container below said bead.

5. A sealed package comprising a container having a bead adjacent the upper end thereof, a bevelled surface intermediate said bead and the rim of the container, a closure cap having a cover portion and a depending skirt, a gasket in the skirt of the cap, said skirt being reformed to extrude the gasket against a container, and means above the gasket engaging the bead on the container to hold the cap in position.

6. A sealed package comprising a container having an annular bead adjacent the upper end thereof, a closure cap having a cover portion and a depending skirt, adapted to be applied to the container without rotation thereof, a bead adapted to receive a gasket in the skirt of the cap, a gasket in said bead, and indentations in the skirt of the cap above said bead engaging and locking with the bead on the container.

7. A sealed package comprising a container having an annular bead thereon and a sealing surface below the bead, a closure cap having a cover portion and a depending skirt, a bead in the skirt of the cap adapted to receive a gasket, a gasket in said bead, said bead being reformed to extrude the gasket against the side wall of the container, and indentations in the skirt of the cap engaging the bead on the container, the reformation of the bead pressing the indentations further inward to lock with the bead of the container.

8. A sealed package comprising a container having an annular bead adjacent the upper end thereof, a sealing surface below said bead, and an inwardly tapered surface above the bead, a closure cap having a cover portion and a depending skirt, a gasket in the lower part of said skirt, and indentations above said gasket engaging the bead on the container to assist in holding the cap thereon, the lower part of said skirt being reformed to press the gasket firmly against the container, said reforming operation being adapted also to constrict said indentations into firmer locking engagement with the bead on the container, the tapered part of the container being adapted to facilitate the removal of the cap from the container.

70 9. A sealed package comprising a container having a projection adjacent the upper end thereof, and a closure cap having indentations in the skirt thereof engaging said projection, and a bead in the skirt provided with a gasket, said bead being reformed to compress the gasket to

engage the container, said bead being adapted to be pried outwardly to release the cap and said indentations being adapted to re-engage said projection after the cap has been removed, to provide means for resealing the cap to the container.

10. A sealed package comprising a container having a projection adjacent the upper end thereof and a closure cap having indentations in the skirt thereof engaging said projection, a bead in the skirt provided with a gasket being reformed 10 to form a hermetic seal upon the container, said bead being adapted to be pried outwardly to break the hermetic seal, and said indentations being adapted to be snapped over said projection after the cap has been removed, to provide means 15 for resealing the cap to the container.

11. A sealed package comprising a container having an outward extension beneath the rim thereof, a closure cap having a cover portion, a depending skirt, a bead in the skirt of the cap, 20 a gasket in said bead, said bead being reformed to compress the gasket against the container, and a plurality of separate locking projections in the skirt of the cap above the gasket adapted to engage beneath said extension to hold the cap on 25 the container.

12. A sealed package comprising a container having a sealing zone provided with an outwardly extending bead and a closure cap having a skirt portion provided with inwardly extending 30 projections forced over and engaging said bead and a reformed bead in said skirt having a gasket therein secured on the sealing zone below said bead on the container.

13. A sealed package comprising a container having means providing a sealing rib thereon, a cap hermetically sealed upon said container by reforming a portion of the skirt thereof and means formed in the skirt of the cap for engaging said rib upon said container whereby means 40 for resealing the cap to the container are provided.

14. The method of sealing a closure cap having inwardly extending projections adapted to engage a rib on a container, and having a gasket seated in a bead below the projections, which method comprises placing said cap upon the container, moving said cap downwardly without rotation thereof to force the projections on the cap beneath the rib on the container to provide 50 a temporary snap-on seal, and thereafter constricting the bead to compress the gasket against the container to provide a hermetic seal.

15. The method of sealing a closure cap having inwardly extending projections adapted to 55 engage a rib on a container and having a gasket seated in a bead below the projections, which method comprises placing said cap on the container, snapping the projections over the rib on the container to provide a temporary seal, 60 thereafter constricting the bead to press the gasket against the container to provide a hermetic seal, and setting said projections further radially inwardly to lock them beneath the rib on the 65 container.

16. A closure cap removable from a container without rotation thereof, comprising a cover portion, a depending skirt having its lower edge turned inwardly to support a gasket, a gasket 70 in the lower portion of the skirt of the cap supported by said inturned edge, and an inwardly extending rib formed in said skirt, said rib extending circumferentially about said skirt and being discontinued at a plurality of portions to 75

provide a plurality of relatively long narrow ribs for snapping over a rib on a container to lock the cap thereon.

17. A closure cap comprising a cover portion, 5 a depending skirt, a bead in said skirt, the bottom of the cap extending inwardly to form the bottom of the bead and to support a gasket, a gasket in said bead, and an inwardly extending rib of substantial depth formed in said skirt above 10 said bead, said rib being discontinued at a plurality of portions to provide a plurality of relatively long narrow ribs slightly below the cover portion and at equal distances therefrom for 15 locking the cap on a container, said locking ribs

being of greater circumferential length than said discontinued portions.

18. A closure cap comprising a cover portion, a depending skirt, a plurality of relatively long circumferentially extending rib portions formed in said skirt for locking the cap on a container all of said rib portions being substantially the same distance from the top of the cap, a bead below 5 said rib portions, said bead being adapted to be reformed and a gasket in said bead, the lower edge of said skirt being set inwardly to form a support 10 for said gasket and to retain said gasket within said bead when said bead is reformed.

CHARLES HAMMER.
